Primary Examiner — T Chase Nelson*Assistant Examiner* — Mary Claire Ramirez(74) *Attorney, Agent, or Firm* — Bayramoglu Law Offices LLC(57) **CLAIM**

The ornamental design for a thermal imaging camera, as shown and described.

DESCRIPTION

FIG. 1 is a front elevation view of a thermal imaging camera showing our new design;

FIG. 2 is a rear elevation view thereof;

FIG. 3 is a left elevation view thereof;

FIG. 4 is a right elevation view thereof;

FIG. 5 is a bottom plan view thereof;

FIG. 6 is a top plan view thereof;

FIG. 7 is a top perspective view thereof; and,

FIG. 8 is a bottom perspective view thereof.

The broken lines depict portions of the thermal imaging camera form no part of the claimed design.

1 Claim, 7 Drawing Sheets(56)
